FOOTWEAR HEEL GUARD

Josephine O. Riemann, Battle Creek, Mich.
Application June 9, 1958, Serial No. 51,253

Term of patent 14 years

(Cl. D7—5)

The broken lines indicating a portion of a slipper are for illustrative purposes only, and the front and bottom of the heel guard are fully open except for a side to side connecting elastic strip at the lower front edge of the heel, a side edge of such strip being shown in Figure 1.

I claim:

The ornamental design for a footwear heel guard, substantially as shown and described.
